a corporation of New York

Application October 29, 1949, Serial No. 5,788

Term of patent 3½ years

(Cl. D3—25)

To all whom it may concern:

Be it known that I, Raissa Masket, a citizen of the United States, residing at New York, in the county of New York and State of New York, have invented a new, original, and ornamental Design for a Blouse or Similar Article, of which the following is a specification, reference being had to the accompanying drawing, forming part thereof.

In the drawing:

Fig. 1 is a front elevational view of a blouse or similar article, showing my new design;

Fig. 2 is a rear elevational view thereof.

Fig. 3 is a section as viewed along the lines 3—3 of Fig. 2.

I claim:

The ornamental design for a blouse or similar article, as shown.

RAISSA MASKET.
